EUGENE G. REISING, OF HARTFORD, CONNECTICUT.

FIREARM.

1,322,053.

Specification of Letters Patent. Patented Nov. 18, 1919.

Application filed November 3, 1915. Serial No. 59,365.

To all whom it may concern:

Be it known that I, EUGENE G. REISING, a citizen of the United States, and a resident of Hartford, in the county of Hartford and 5 State of Connecticut, have invented a new and Improved Firearm, of which the following is a specification.

My invention relates more especially to that class of firearms that are designed to 10 be supported by the person when discharged, and an object of my invention, among others, is to provide a firearm that shall be simple in its construction and operation, and particularly effective and efficient in the results 15 produced.

One form of firearm embodying my invention and in the construction and use of which the objects herein set out, as well as others, may be attained, is illustrated in the 20 accompanying drawings, in which—

Figure 1 is a view in side elevation of the rear portion of a firearm embodying my invention.

Fig. 2 is a side view, scale enlarged over 25 Fig. 1, of my improved firearm shown as partially broken away in central lengthwise section and with the breech-bolt in its forward position.

Fig. 3 is a similar view showing a part of 30 the device illustrated in Fig. 2 and with the breech-bolt in its rearward position.

Fig. 4 is a view in cross section on plane denoted by dotted line 4—4 of Fig. 2 looking toward the front.

35 Fig. 5 is a top view with parts broken away to show construction.

Fig. 6 is a detail side view of the receiver shown as cut away in central section.

Fig. 7 is a detail side view of a portion 40 of my improved firearm showing the receiver in side elevation.

Figs. 8, 9 and 10 are detail views illustrating the construction of the cartridge carrier.

45 Fig. 11 is a detail side view of the breech-bolt.

Fig. 12 is a detail view in cross section through the breech-bolt on plane denoted by dotted line 12—12 of Fig. 11.

50 Fig. 13 is a detail view, looking downward, of a portion of my improved firearm cut in section through the breech-bolt and illustrating the construction and operation of the breech-bolt retractor.

55 Fig. 14 is a detail view illustrating the

construction of the latch for holding the magazine in place.

While my invention is not confined to a firearm of any special type, as it readily adapts itself to the so called class of "automatics," I have selected one of this type for the purpose of illustrating my invention herein, and in the accompanying drawings the numeral 20 denotes the stock of my improved firearm, including a fore-end 21, 60 which parts may be constructed of wood shaped to receive the metallic parts of the gun in any well known manner, and which metallic parts include a receiver 22 having a barrel 23 secured to it in any desired 65 manner. This receiver is in the form of a housing, open at the bottom and at the rear end, the front end being closed by a wall 24 having openings through one of which a magazine tube and carrier operating lever to 70 be hereinafter described extends, and also having recesses 81 and 82 to receive the fore-end and trigger guard plate. This receiver or housing has also an ejector opening 25 in one side wall, both walls having ears 26 75 between which the front end of the stock is received and to which it is secured. A trigger guard plate 27 fits between the side parts of the receiver at its lower edge, closing the bottom opening thereto, the front end of this plate being shaped for reception 80 within a lip 28 at the edge of the recess 82, and the rear end 29 of said plate 27 extends upwardly between the side parts of the receiver to the upper wall thereof closing the 85 back end of the receiver and thus forming a chamber 62 within which the firing mechanism is located. An opening 30 extends through this rear end 29 and the trigger guard plate has the usual trigger guard 32 90 and a rearward extension 31 terminating in an upwardly extending lug 33.

A hanger 34 is secured to the barrel 23 and within the fore-end 21, and a magazine tube 35 projects through this hanger into 100 an opening 36 in the wall 24, this tube being removably secured in place as by means of a screw 37 in the hanger 34.

A tubular magazine 38 is removably located within the tube 35, and is held in place 105 as by means of a pivotally mounted latch 39 receiving thrust of a follower spring 83 and pressed thereby into an opening through the side wall of the magazine tube, there being a spring pressed follower 40 located within 110

the tube in a manner common to devices of this kind.

The side walls of the receiver are cut away in a vertical direction forming recesses 41 within which a cartridge carrier 42 is mounted to slide in a vertical direction, upward movement being imparted to the carrier by a carrier operating lever 43 pivotally secured in a hanger 44 attached to the 10 under side of the barrel, the rear end of this lever being pressed upwardly as by a spring 45 located between the front end of the lever and the under side of the magazine tube, which tube also passes through the hanger 44. The lever 43 is pivotally mounted in a 15 chamber 67 within the fore-end 21, the lever extending from said chamber through an opening 68 into the firing mechanism chamber 62. The carrier rides loosely upon the 20 spoon shaped end of the lever 43 that is located in a groove 46 in the under side of the carrier. A rounded formation 48 appears upon the upper surface of the cartridge carrier at its rear end, and within which a cartridge recess 47 is partially formed, said recess extending in the upper surface of the cartridge carrier between rising side walls 49, the upper edges of which are adapted to strike against the shoulders formed at the 25 extreme top of the recesses 41, ledges 50 on opposite sides of the rounded formation 48 being adapted to strike shoulders 51 located near the upper ends of the recesses 41 but below the extreme upper sides thereof.

30 A breech-bolt 52 is mounted for sliding movement in the upper part of the chamber within the receiver, and in position to pass over the upper edge of the carrier, ribs 53 extending lengthwise along 35 opposite sides of the breech-bolt being located in breech-bolt grooves 54 extending along the walls of the receiver and oppositely arranged therein. The breech-bolt has side parts 55 at its front end extending 40 for a portion of the distance backwardly, the rear end of the bolt being solid down to the lower edges of these side parts. The front end of each of these side parts is beveled at 56 to correspond with the beveled 45 rear ends 57 of the carrier 42, so that as the breech-bolt is forced forward, its beveled edges striking the beveled edges of the carrier will force the latter downwardly into the position shown in Fig. 2 to receive a 50 cartridge from the magazine 38, which cartridges being forced backwardly by the follower 40 strike the rear wall 58 of the recess 47 in the carrier, this correctly positioning a cartridge in the carrier for delivery into 55 the breech-opening in the barrel. A cartridge fed rib 59 extends lengthwise along the top wall of the recess between the sides 55 on the breech-bolt and in position to engage the upper edge of the cartridge shell 60 60 and force the cartridge to place in the

barrel. The breech-bolt will be provided with an extractor 60 and a firing pin 61 of any desirable construction, said pin, as the breech-bolt is moved backwardly, striking the rear wall of the chamber 62 and acting 70 as an ejector, as illustrated in Fig. 3 of the drawing.

A hammer 63 is pivotally mounted within the chamber 62 and is forced forward by a hammer spring 64 mounted on a hammer actuating bar 65 projecting at one end through an opening 66 in the front wall of the chamber 62 in the receiver. The spring 64 rests with one end against the front wall of the chamber 62 and thrusts with its opposite end against a shoulder on the bar. A sear 69 is pivotally mounted in the chamber 62, its front end being forced by a spring pressed plunger 70 into position to engage notches in the hammer in a well known manner. A sear actuating lever 71 is pivoted on the trigger guard plate 27, its pivot 72 being located in a slot in the lever that permits its rearward movement caused by the sear lever actuating cam 73 at the front end 90 of a slot 74 in the trigger guard plate, in which slot the trigger 75 is pivotally mounted. When the trigger is pulled backwardly the front end of the sear actuating lever is raised, the sear actuating prong 95 thereon engaging the sear and disengaging it from the hammer. In this rising movement of the front end of the lever its engagement with the cam 73 causes it to move backwardly, disengaging the prong 76 from the sear and permitting the plunger 70 to quickly move the sear into position to again engage a notch in the hammer upon the next rearward movement of the latter. This prevents an unintentional discharge of the 105 firearm. A sear lever actuating plunger 77 presses against the rear end of the lever, forcing it forward and its front end downwardly.

The back end of the breech-bolt is beveled 110 forwardly from the top downwardly, this beveled surface terminating in a projection 90 extending slightly below the bottom of the breech-bolt, which projection is adapted to engage a projection 91 located on the 115 front edge of the hammer between its ends. The object of this construction is to enable the greater part of the cocking movement of the hammer to be obtained at the initial movement of the breech-bolt, at which time 120 the power exerted on the breech-bolt is the greatest. After the hammer is cocked the projection on the breech-bolt, coöperating with that on the hammer, having effected its purpose the breech-bolt is free to move 125 and complete its backward movement, at a time when the power to move it is much reduced, with little, if any, obstruction to such movement by the hammer.

A breech-bolt actuating lever 78 is piv- 130

totally mounted in the chamber 62, preferably upon the pivot for the sear 69. The end of this lever opposite its pivot rests against the rear end of the breech-bolt and a breech-bolt actuating bar 79 is pivotally connected with the lever 78 and projects backwardly through an opening in the lug 33, a breech-bolt actuating bar spring 80 pressing with one end against said lug and 10 the other against a shoulder on the bar. The lever 78 is of angular shape and the bar 79 is so disposed and attached to the lever at such point that the resistance to opening movement of the breech-bolt is on a line 15 passing close to the pivotal point of connection of said bar to the lever but at one side thereof. This causes said force to be applied almost on the "dead center" so that the resistance to opening movement of the 20 breech-bolt is very great at the beginning of such movement, but this resistance is rapidly decreased after the initial rearward movement of the breech-bolt takes place.

While I have shown and described herein 25 a satisfactory arrangement and construction of mechanism for accomplishing my purpose, this may be departed from to a greater or lesser degree and yet be within the spirit and intent of the invention.

30 A breech-bolt retracting lever 84 is pivotally mounted in a recess in the side of the breech-bolt, its outer end or finger piece projecting into the opening 25, as shown in Fig. 13. The inner end of this lever is 35 adapted to strike the wall of the recess 85 when the lever is swung to its operative position to retract the breech-bolt, and a spring actuated plunger 86 presses against the inner end of the lever and tends to hold 40 it in its inoperative or closed position. By moving the lever outwardly to the position shown in dotted lines in Fig. 13 its inner end will strike against the wall of the recess 85 and the breech-bolt may be moved 45 backwardly into firing position, this for the purpose of starting the firing operation should the breech-bolt happen to be in its forward or closed position.

50 A positioning pin 87 for the breech-bolt actuating lever 78 is adjustably mounted in the trigger plate, preferably this pin being screw threaded to fit a threaded opening in the plate and its end having a slot by means of which it may be turned. The inner end 55 of this pin is located to be engaged by a positioning prong 88 extending from the breech-bolt actuating lever 78, as clearly illustrated in dotted lines in Fig. 3 of the drawings. The end of the lever 78 in engagement with the breech-bolt is rounded 60 to engage the beveled rear surface of the bolt, and the formation of the engaging surfaces of the breech-bolt and lever and the lever itself are so disposed as to cause 65 the force of the breech-bolt upon the lever

to pass close to but at one side of the pivot for the lever, so that the resistance to opening movement of the breech-bolt will be very great at the beginning of such movement but will be rapidly decreased as such 70 opening movement continues. By means of the positioning pin 87 the lever may be so located that this line of force may be caused to pass nearer to or farther from the pivotal point of support of the lever. 75

The bottom of the carrier 42 is of such thickness that when the carrier is in its uppermost position, and as indicated in Fig. 3, the bottom of the carrier will partially obstruct the opening into the magazine and 80 thus retain the cartridges in place in the magazine; the bottom of the carrier thus acting as a "cut-off" to so retain the cartridges in place. 85

I claim—

1. A firearm including a receiver having side walls with vertically extending recesses of a width equal to the length of the following mentioned carrier oppositely disposed therein, said recesses having stop 90 shoulders, a breech-bolt slidably mounted between said side walls, means for actuating the breech-bolt, a carrier extending between said side walls, the full side surfaces of the carrier extending into said recesses 95 and into guiding engagement therewith, the top of said carrier being adapted to engage said shoulders that form stops therefor, means for operating the carrier, firing mechanism, and means for supplying 100 cartridges to said carrier.

2. A firearm including a receiver containing a chamber having side walls with vertically extending recesses oppositely disposed therein and with stop shoulders located below the top of said chamber and facing downwardly, a breech-bolt slidably mounted between said side walls, means for actuating the breech-bolt, a carrier extending between said side walls, the side surfaces of the carrier extending into said recesses and into guiding engagement therewith, ledges upon the carrier to engage said stop shoulders, said ledges being formed of the substance of the body of the carrier 110 and below the top thereof, means for operating the carrier, firing mechanism, and a magazine to deliver cartridges to said carrier. 115

3. A firearm including a receiver having 120 side walls with vertically extending recesses oppositely disposed therein, said recesses having top edges and stop shoulders located below said top edges, a breech-bolt slidably mounted between said side walls, 125 means for actuating the breech-bolt, a carrier having its sides extending into said recesses and having ledges to strike said stop shoulders and top edges to strike the top edges of said recesses, means for operat- 130

ing the carrier, firing mechanism, and means for supplying cartridges to said carrier.

4. A firearm including a receiver having side walls with vertically extending recesses oppositely disposed therein, said recesses having stop shoulders extending partially across each recess and facing downwardly, a breech-bolt slidably mounted between said side walls, means for actuating the breech-bolt, a carrier extending between said side walls and into said recesses and having ledges to engage said shoulders, and projections rising above said ledges to pass into openings in front of said shoulders, means for operating the carrier, firing mechanism, and a magazine to deliver cartridges to said carrier.

5. A firearm including a receiver, a magazine, a carrier movably mounted in the receiver to obtain cartridges from said magazine, a projection rising above a part of the carrier and providing stop shoulders on each side thereof and having a cartridge recess therein, a breech-bolt slidably mounted in the receiver and above the carrier and having a rib to enter said recess to remove a cartridge therefrom as said bolt passes over the carrier, means for actuating the breech-bolt, and firing mechanism.

6. A firearm including a receiver, a magazine, a carrier movably mounted in the receiver to obtain cartridges from said magazine, a projection rising above a part of the carrier and having a cartridge recess therein, a breech-bolt slidably mounted in the receiver and having a recess to receive the projection on the carrier and a rib to enter the recess in the carrier to remove a cartridge therefrom, means for actuating the breech-bolt, means for operating the carrier, and firing mechanism.

7. A firearm including a receiver, a magazine, a carrier movably mounted in the receiver to obtain cartridges from said magazine, said carrier having side walls with beveled rear edges, a projection rising from a portion of the carrier between said edges and having a cartridge recess, a breech-bolt slidably mounted within the receiver and having side parts with beveled edges oppositely disposed to those on the carrier, said bolt being positioned to receive between its side parts the projection from the carrier, a rib on the bolt in position to pass into the recess in the carrier to remove cartridges therefrom, means for operating the breech-bolt, means for operating the carrier, and firing mechanism.

8. A firearm including a receiver, a magazine, a carrier movably mounted in the receiver to obtain cartridges from said magazine, said carrier having side walls with beveled rear edges terminating in ledges at the rear end thereof, a projection rising above said ledges and between said side

walls and containing a cartridge recess, a breech-bolt slidably mounted in the receiver and having side walls with beveled edges to coöperate with those on the carrier to operate the latter, a rib on the breech-bolt positioned to enter said recess and remove cartridges therefrom, means for actuating the breech-bolt, means for actuating the carrier, and firing mechanism.

9. A firearm including a receiver, a magazine, a carrier movably mounted in the receiver to obtain cartridges from said magazine, said carrier having side parts with beveled rear edges terminating in ledges, a projection rising above said ledges and between the side parts and having a cartridge recess, a breech-bolt having side parts between which the projection on the carrier is received, the side parts on the breech-bolt being beveled to coöperate with those on the carrier to operate the latter, a rib on the breech-bolt between its side parts to enter the cartridge recess in the carrier to remove cartridges therefrom, the lower edges of the side parts on the breech-bolt being located above the ledges on the carrier when the breech-bolt is in its closed position, means for operating the breech-bolt, means for operating the carrier, and firing mechanism.

10. A firearm including a receiver, a magazine, a carrier movably mounted in the receiver to obtain cartridges from said magazine, a ledge extending forwardly from the rear edge of the carrier, beveled portions extending upwardly from said ledge, said carrier having a recess to receive a cartridge, a breech-bolt slidably mounted in the receiver above the carrier and having a beveled portion to engage the beveled portion on the carrier, the bottom of said bolt being adapted to pass over said ledges in the forward movement of the breech-bolt, a rib on the bolt to enter said recess in the carrier, means for actuating the breech-bolt, and firing mechanism.

11. A firearm including a receiver having at its front end a wall to a chamber therein, said wall having openings therethrough, a barrel secured within one of said openings, a hanger secured to the barrel and depending therefrom, a carrier operating lever pivotally mounted in said hanger and extending through an opening in said front wall into the chamber in the receiver, a carrier operatively connected with said lever and a breech-bolt and firing mechanism located in the chamber in the receiver.

12. A firearm including a receiver having a wall to a chamber therein with openings through said wall, a barrel secured within one of said openings, a hanger secured to and depending from the under side of the barrel, a magazine projecting through the hanger and through one of the openings in said wall

of the receiver, a carrier lever pivotally mounted in the hanger and projecting through an opening in said wall to the chamber within the receiver, a carrier operatively connected with said lever and a breech-bolt and firing mechanism located within the chamber within the receiver.

13. A firearm including a receiver having at its front end a wall to a chamber therein with openings through said wall, a barrel secured within one of said openings, a stock to support said receiver said stock having a chamber therein underlying the barrel, a hanger secured to the barrel and depending therefrom within the chamber in the stock, a magazine projecting through said hanger and into an opening in said wall of the receiver, a carrier lever pivotally mounted in said hanger and projecting through an opening into the chamber in the receiver, a carrier operatively connected with said lever, a breech-bolt and firing mechanism located in the chamber in the receiver.

14. A firearm including a receiver, a breech-bolt mounted within the receiver, a pivotally mounted breech-bolt actuating lever in engagement with the breech-bolt, means for actuating said lever, a member movably mounted to determine the forward position of said lever at each active reciprocating movement thereof and firing mechanism to coöperate with the breech-bolt.

15. A firearm including a receiver, a breech-bolt movably mounted within the receiver, a pivotally mounted breech-bolt actuating lever having a forward projecting prong, means for actuating said lever, an adjusting member movably mounted underneath said prong to determine the forward position of said lever and firing mechanism to coöperate with the breech-bolt.

16. A firearm including a receiver, a breech-bolt movably mounted therein, a trigger plate secured to the receiver, a breech-bolt actuating lever pivotally mounted on the trigger plate and having a forward projecting prong, means for actuating said lever, an adjusting screw projecting through said plate to adjust said prong, and firing mechanism to coöperate with said breech-bolt.

17. A firearm including loading mechanism therefor, and firing mechanism including a hammer, a sear, a slidable pivotally mounted sear actuating lever projecting through an opening in the bottom of the frame into the inclosure within the trigger guard, said opening having its edge formed into a cam to cause sliding movement of said lever to disengage it from the sear, means for forcing the lever in the opposite direction, and a trigger pivotally mounted in said opening to engage said lever to operate it.

65. 18. A firearm including a frame having a

chamber therein containing loading mechanism, firing mechanism located in said chamber and including a hammer, a sear pivotally mounted on the bottom of said chamber to engage the hammer, a slidable pivotally mounted sear actuating lever mounted in the bottom of said chamber in extension of said sear and having a prong to engage said sear, a cam extension projecting through an opening from said chamber into the inclosure within the trigger guard, a cam formed on the edge of said opening to engage said lever to operate it, and a trigger pivotally mounted in said opening to engage said lever to actuate it.

19. A firearm including a receiver, a breech-bolt slidably mounted in the receiver and having a beveled surface, a hammer pivotally mounted in the receiver and having a projection intermediate its ends to receive said beveled surface to effect cocking movement of the hammer in an initial movement of the breech-bolt, and means for actuating the hammer.

20. A firearm including a receiver, a breech-bolt slidably mounted in the receiver and having a beveled surface on its back lower edge with a projection at the end of said beveled surface, a hammer pivotally mounted in the receiver and having a projection intermediate its ends to engage said beveled surface to effect cocking of the hammer in the initial movement of the breech-bolt, and means for actuating the hammer.

21. A firearm including a receiver, a breech-bolt slidably mounted in the receiver, a hammer pivotally mounted in the receiver and having a projection to engage the breech-bolt to effect cocking movement of the hammer in the initial movement of the breech-bolt, a projection on the lower back end of the breech-bolt to engage said hammer to remove the latter from engagement with the breech-bolt before the breech-bolt completes its backward movement, and means for actuating the hammer.

22. A firearm including a receiver, a breech-bolt slidably mounted therein, a pivotally mounted angularly shaped breech-bolt actuating lever located within the chamber in the receiver to engage the breech-bolt, said lever being rigid and engaging the breech-bolt at that end opposite its supporting pivot, the pivot of said lever being located nearly in line with the direction of the force applied to the breech-bolt to open it and the engaging angularly shaped part of the lever projecting forwardly when the breech-bolt is closed, means for actuating the lever, and firing mechanism to coöperate with the breech-bolt.

23. A firearm including a receiver, a breech-bolt slidably mounted in the receiver and having a beveled rear face, a pivotally

mounted angularly shaped breech-bolt actuating lever located in the chamber in the receiver and loosely engaging the breech-bolt and with its pivot positioned nearly in line with the direction of force applied to the breech-bolt in its opening movement and the engaging angularly shaped part of the lever projecting forwardly when the breech-bolt is closed, means for actuating the lever, and firing mechanism to coöperate with said breech-bolt.

24. A firearm including a receiver, a breech-bolt slidably mounted in the receiver, an angularly shaped pivotally mounted breech-bolt actuating lever located in the chamber in the receiver, a bar extending substantially in line with that part of said lever in engagement with the breech-bolt and operatively connected with said lever,

the breech-bolt having an inclined surface 20 extending nearly at right angles to a line passing through said bar and the outer end of said lever, means for forcing said bar forward, and firing mechanism to coöperate with said breech-bolt. 25

25. A firearm including a receiver having a discharge opening therein, a breech-bolt slidably mounted in the receiver and having a recess in its side, a breech-bolt actuating lever pivotally mounted on the breech-bolt 30 within said recess and extending out of said opening, and a rigid stop to limit the swinging movement of said lever.

EUGENE G. REISING.
